ABSTRACT

A circular hosiery knitting machine closes the toe pocket of hose during its formation, the toe closure is accomplished by holding the starting end of suitable yarn, forming a selvage course of the yarn spaced needles by rotary knitting, forming a plurality of following courses of the yarn upon progressively increasing numbers of needles by rotary knitting until all of the needles are so used, exerting yieldable tension upon the starting end of the yarn during the formation of the courses thereby diametrically constricting the same, the so constricted courses progressively increasing in size and in number of wales to form a circularly shaped fabric area extending across the bore of the needle cylinder, discontinuing the tension on the starting end of the yarn and knitting the remainder of the hose on the needles, the circular fabric constituting the closed toe pocket. Apparatus on the machine including a hook to engage and to pull the yarn, extending from its guide to a first clamp on the machine, to transfer the starting end of the yarn from the first clamp to be held in a second clamp spaced from the needle cylinder and a spring mounted roller to deflect the yarn extending between the second clamp and the needle cylinder to tension the starting end of the yarn.

KNITTING OF STOCKING TOES ON CIRCULAR KNITTING MACHINES

The present application is a division of application Ser. No. 851,265, filed Aug. 19, 1969, now abandoned.

The present invention relates generally to the art of knitting and more particularly to hosiery and to the method and machine for the production thereof, and has particular reference to the foot portion of hosiery which is provided with a closed toe made of a single ply of circularly knit plain fabric and which is closed during the formation thereof by rotary knitting on a circular knitting machine.

As set forth in U.S. Pat. No. Re. 26,580, hosiery having a closed toe made by rotary knitting during the formation thereof has heretofore been produced. Such closed toe hosiery is made upon a circular knitting machine which must be equipped with a welt transfer dial in order to make the two ply turned welt of which the closed toe is formed. Such closed toe is made of two plies of unshaped tubular fabric which are relatively twisted, prior to the closure of the welt, to constrict the fabric to form the toe closure which is never really closed and which is bulky due to the two plies and to the presence of the twisted fabric at the end of the toe. Other hosiery having a closed toe made by rotary knitting during the formation thereof has also been heretofore produced, as set forth in the Italian Pat. No. 814,164. Such other hosiery differs from that disclosed in the U.S. Patent in that the two ply welt is constricted by turns of yarn wound around the fabric of the interior of the welt at its fold line.

The closed toe hosiery of the present invention is superior to the hosiery of the above set forth prior art in that the toe is less bulky since it is made of a single ply only of plain knit fabric and it is better fitting since the fabric forming the toe is shaped to fit the toe during the knitting. Furthermore, the closed toe of the present invention can be made upon a much simpler machine since the welt transfer dial is not needed therefor, and, in addition, the time required to make the present closed toe is approximately half the time required to make the above prior art toes, since only half the amount of fabric is required.

It is the principal object of the present invention to provide closed toe hosiery having a toe formed of a circularly shaped area of plain knit fabric comprising a plurality of circularly knit courses progressively increasing in size and in number of wales, and to provide a machine and a method to make the same.

It is a further object of the present invention to make the circularly shaped area of plain knit fabric by rotary knitting upon a circle of needles of a circular knitting machine by holding the starting end of a suitable yarn, knitting a selvage course of the yarn upon spaced needles of the circle of needles, knitting a plurality of following courses of the yarn upon progressively increasing numbers of the circle of needles until all of the needles are so used and exerting tension upon the starting end of the yarn during the formation of the courses to diametrically constrict the same, the constricted courses progressively increasing in both size and in number of wales to provide the circularly shaped plain knit fabric area.

It is a still further object to provide apparatus to hold the starting end of the yarn and to apply tension thereon during the knitting thereof, including means to transfer the starting end of the yarn from a first clamp

inside the circle of needles to a second clamp spaced therefrom.

Other objects and advantages of the invention will become apparent from the following detailed description of preferred embodiments of the present hosiery and of the machine and method to make the same, as shown in the accompanying drawings and as pointed out in the appended claims.

IN THE DRAWINGS:

FIG. 1 is a diagrammatic view in perspective of a number of consecutive latch needles and sinkers of circular series thereof at the start of the process of knitting the fabric for a closed toe pocket for the foot portion of hosiery, according to the present invention.

FIGS. 2, 3, 4, 5, 6, 7, and 8, are views similar to FIG. 1 and show subsequent steps in the process of knitting the closed toe pocket for the foot portion of hosiery, according to the present invention.

FIG. 9 is a diagrammatic plan view of the stitches and of the constricted courses of fabric made in accordance with the process shown in FIGS. 1-8, the fabric being partially completed and still on the circle of needles with the starting end of the yarn extending across the circle of needles from the start of the still open selvage course.

FIG. 10 is a view similar to FIG. 9 showing a modified form of selvage course with a pair of turns of the yarn therein.

FIG. 11 is a perspective view of the upper end of portions of a circular knitting machine showing the yarn being fed to the needles and showing the starting end of the yarn extending from its point of attachment in the partially constricted selvage course of the partially formed circularly knit toe pocket fabric to, and through, an aperture in the latch ring to the means exerting tension upon the yarn, the fabric courses being partially constructed and extending in a horizontal plane.

FIG. 11A is a schematic plan view, in reduced size, of the completed toe pocket fabric wherein its courses have been constricted sufficiently to fully close the opening initially present in the fabric as it is being formed and which is shown partially closed in FIGS. 9, 10 and 11, the completed fabric being circularly shaped and extending across and covering the bore of the needle cylinder;

FIG. 12 is a view in side elevation of the closed toe pocket and part of the foot portion of hosiery made with the circularly shaped knit fabric of FIG. 11A according to the present invention;

FIG. 12A is a view in side elevation of the reverse side of the toe and foot portion of FIG. 12 and shows the starting end of the yarn extending from the center of the circularly shaped knit fabric of the pocket.

FIG. 13 is a view similar to FIG. 12 and showing a first modification of the closed toe pocket which also contains a narrowed and widened segment of fabric which is disposed on the under-the-toe side of the toe pocket while the circularly shaped knit fabric is disposed on the over-the-toe side of the toe pocket;

FIG. 14 is a view in side elevation of hosiery made upon a circular knitting machine and having a foot portion embodying the present invention, the closed toe pocket itself showing a second modification thereof which differs from the first modification of FIG. 13 in that the narrowed and widened segment of fabric is

herein disposed on the over-the-toe side of the toe pocket while the circularly shaped fabric is disposed on the under-the-toe side of the toe pocket;

FIG. 15 is a side elevational view of an attachment which co-operates with the circular knitting machine to aid in carrying out the process of the present invention, the attachment providing the means to hold the starting end of the yarn and to apply tension thereto during the knitting of the circularly shaped fabric area, the yarn engaging hook of the attachment being inside the periphery of the circle of needles in this view;

FIG. 16 is a view similar to FIG. 15, on an enlarged scale, showing the hook in withdrawn position with engaged yarn also withdrawn into position within an opened clamp;

FIG. 17 is a view similar to FIG. 16 showing the yarn held in the closed clamp and showing tension being applied by rollers to the yarn extending between the clamp and the circle of needles;

FIGS. 18 and 19 are plan views of the apparatus as shown in FIGS. 15 and 16, respectively, and

FIGS. 20 and 21 are sectional views taken on lines XX — XX and XXI — XXI of FIGS. 15 and 19 respectively.

The present invention will be set forth in two parts, the first of which is related to the FIGS. 1 — 14, and the second of which is related to the FIGS. 15 — 21. The FIGS. 1 — 14 illustrate the product of the invention and the process of forming the same upon the needles of a circular knitting machine during which it is required that the starting end of the yarn to be knit be held and be subjected to yieldable tension during the knitting thereof. Such holding and tensioning of the starting end of the yarn may be provided in any desired manner, as by hand or by apparatus, of which one form thereof is shown in FIGS. 15 — 21. Accordingly, the invention will be described in relation to FIGS. 1 — 14 without regard to the particular manner in which the starting end of the yarn is held and tensioned, and, thereafter, the apparatus of FIGS. 15 — 21, which is in the form of an attachment to the machine itself, will be described to show one way of holding and tensioning the starting end of the yarn.

The product of the present invention is shown in FIGS. 12, 13 and 14, of which FIG. 12 shows the closed toe pocket T, at the end of part of a foot portion F of hosiery, the pocket being formed of a circularly shaped fabric area indicated at 6. The FIG. 12A shows the product of FIG. 12 turned inside out with the starting end of the yarn of which the fabric 6 is knit shown extending from the center of the fabric 6 at 5a. The FIG. 13 shows a first modification of the closed toe pocket which is formed of a narrowed end widened segment of fabric N in addition to the circular fabric 6, with the fabric on the sole side Ta of the toe and the fabric 6 on the instep side Tb of the toe. The FIG. 14 shows a complete hose made on a circular knitting machine and having, in addition to the foot F and a second modification of the toe T, a welt W, a leg L, and a heel pocket H. The toe pocket of FIG. 14 is also formed of a narrowed and widened segment of fabric N in addition to the circular fabric 6, with the former now on the instep side Tb of the toe and with the latter now on the sole side Ta of the toe.

Inasmuch as the present invention is concerned with the improved toe closure for the foot portion of hosiery, or the like, of all types including boys, men's, la-

dies and pantyhose, it follows that the remaining portions of the hosiery may be made in any desired manner consistent therewith, the showing in FIG. 14 being merely illustrative of one type of hosiery embodying the present invention. The principle of the present invention may also be used to provide a closed end pocket for tubularly formed finger, hand and head coverings, or for any tubularly knit product in which it is desired to have at least one end thereof closed.

10 The present invention may be made upon any conventional circular knitting machine having a removable circle of needles in a moving needle cylinder (the needles and cylinder rotating to make the toe of FIG. 12 and also reciprocating to make the toes of FIGS. 13 and 14), sinkers associated with the needles, needle selecting means, a clamp and cutter for the yarn at the upper end of the needle cylinder, a latch ring and all the other usual parts thereof. Portions of such a machine are shown in FIG. 11 wherein 1 indicates a needle cylinder having therein the usual circle of vertically arranged needle slots within which needles 2 of a circle of needles are disposed for sliding movement therein. At the upper end of the needle cylinder there is a circle of radially slidable sinkers 3, alternating with the hook ends 25 of the needles 2, the sinkers being so movable in slots in a circular sinker bed secured to the upper end of the needle cylinder, the sinker bed being covered by a sinker cap 4 which contains the usual cams to actuate the sinkers. Also provided is one of the usual plurality of yarn guides, as shown at 7, in lowered feeding position to feed a yarn 5 to the needles 2 which, by rotary knitting, have already made the circular fabric 6 of which the present novel toe pocket is to be formed. It will be noted that a length of yarn indicated at 5a in 30 FIG. 11, and which is the starting end of the yarn 5, extends from its point of attachment with the starting course of the fabric 6 to, and through, an aperture 23 formed in the periphery of the usual latch ring, a portion only of which is shown at 22 in FIG. 11. The yarn end 5a extends beyond the latch ring 22 and is there held and subjected to the yielding tension, by the attachment shown in FIGS. 15 — 21, forming a part of the present process. It may be noted here that the portion 35 of the yarn length 5a extending between aperture 23 and its point of attachment with the fabric 6 will assume a variety of positions in response to rotation of the fabric 6 with the needles 2, some of which are indicated by the dotted lines. Also, that the length of the portion of the yarn 5a extending between the fabric 6 and the latch ring 22 will vary during the rotation of the fabric as the point of attachment of the yarn 5a with the fabric 6 moves toward and away from the aperture 23, the tension on the yarn 5a drawing it through the aperture when permitted to do so. The starting end 5a of the yarn is under tension exerted in the direction of the arrow and this causes the courses of the fabric to be 40 yarn-robbed whereby their diameters are reduced and their circumferences constricted, as will be explained in connection with the FIGS. 1 — 10. In FIG. 11, the amount of fabric 6 already made is not in itself sufficient to permit the initially formed opening therein to be fully closed although such opening has been partially closed with the fabric extending generally horizontally.

45 In the FIGS. 1 — 10, FIGS. 1 — 8 schematically show the present process carried out on a group of needles of a circle thereof and the product made thereby upon

the circle of needles is shown schematically in FIGS. 9 and 10, with the product in FIG. 10 being a modification of that shown in FIG. 9. The particular number of needles in the needle cylinder, as well as the diameter thereof, may vary so long as the number of needles used can be divided into groups of needles, each of which is sufficient to carry out the process. In the present instance, only 48 needles are shown in FIGS. 9 and 10, for ease of illustration, and these are divided into six groups of eight needles and which are shown in FIGS. 1 - 8 wherein each pair of spaced needles, marked *a* and *b*, have seven needles, marked *c*, *d*, *e*, *f*, *g*, *h*, and *i*, disposed therebetween. The needles are initially bare and the needle *a*, at the top of FIG. 9, of the circle of needles, which move in counter-clockwise direction, is the first needle to receive the yarn 5 of which the product is to be made.

As shown in FIG. 1, every eighth needle 2, of which needles *a* and *b* are a pair, are selected to take the yarn 5 during the first rotation of the needle cylinder, the intervening needles, *c* through *i*, remaining at non-yarn-taking welt level while all the needles *a* and *b* are preferably at tuck level at the single feed of the machine at which the yarn is being fed to the needles and at which the needles are lowered to stitch forming level. The yarn taken by the needles *a*, *b*, of which there are six, during the first rotation of the needle cylinder is indicated at 10. It may be well to point out that the machine is provided with needle selecting means which will permit selected needles to pass the yarn feed at welt, tuck or latch clearing levels and that those needles not selected to be raised at the feed will continue to pass the same at the welt level.

In the second rotation of the needle cylinder, the six spaced needles *a*, *b*, and the now selected six intervening bare needles *f*, pass the feeding station at latch clearing level (the yarn course 10 now being below the opened latches of needles *a*, *b*, and take yarn to form course 11 thereof, the needles *a*, *b*, forming stitches drawn over one side of the yarn course 10 as it is cast off from the needles *a*, *b*, while the needles *f* simply tuck the yarn and draw it over the other side of the yarn course 10 without forming stitches, at this time, as shown in FIG. 2. The result of such action upon the 30 yarn by the needles *a*, *b*, and *f*, in the two rotations of the needle cylinder is to form a starting selvage course, as may be seen in detail at the center of FIG. 9 wherein the yarn course 10 is not knitted, having been cast off from the spaced previously bare needles *a*, *b*, and which now appears as a turn of yarn within the stitches formed of the course 11.

It may be well to pause at this point in the description of the process to discuss the tension to be applied to the end 5a of the yarn 5. During the formation of the courses which make up the product in FIGS. 9 and 10, the starting end of the yarn 5 is subjected to a sufficient amount of yieldable take-up tension by, for example, the apparatus of FIGS. 15 - 21, to subject the yarn in the courses as they are being formed to yarn-robbing tension, with the result that these courses are progressively reduced in diameter and are accordingly circumferentially constructed. Such construction appears in FIG. 9 (and FIG. 10), where the selvage course 10, 11, and the following courses 12 through 19 are of progressively increasing diameters so that the fabric, instead of being tubular in form, now is in the form of a flat circular area extending between, and covering, the bore of

the needle cylinder. In FIG. 9 (and FIG. 10), the number of constructed courses made is not yet sufficient to provide for the full closure of the opening shown inside the selvage course 10, 11, and this permits the stitch arrangement of the selvage course to be clearly illustrated. When a sufficient number of constructed courses have been made, the opening at the center of the fabric, as in FIGS. 11A, 12, 13, and 14, can be made of such a minimum diameter as to be practically invisible, or, if desired, by discontinuing the tension upon the yarn 5a at the proper time, the opening may be made of any desired size. While the tension may be applied to the end of the yarn 5a after a number of courses have been knit, it may also be applied as soon as a sufficient number of needles have taken the yarn and, in welt position, are holding it inside their lowered hooks and in the throats of the advanced sinkers so that the tension on the yarn will not in itself cause slippage of the yarn past such needles and sinkers.

20 Now to return to the process, in the third rotation of the needle cylinder, shown in FIG. 3, the same needles *a*, *b*, and *f*, take the yarn of course 12 and knit the stitches thereof. This same thing is repeated during the 25 fourth and fifth rotations of the needle cylinder wherein the same needles, *a*, *b*, and *f*, take the yarn of courses 13 and 14 and knit the stitches thereof, as in FIG. 4.

In the sixth rotation of the needle cylinder, FIG. 5, the needles *a*, *b*, and *f*, and the now selected intervening bare needles *d* and *h*, pass the feeding station at latch clearing level and take the yarn to form course 15 thereof, the needles *a*, *b*, and *f*, forming regular stitches in their wales while the needles *d* and *h* merely tuck the yarn as shown at 15a to start new wales. In the seventh, eighth and ninth rotations of the needle cylinder, FIG. 6, the same needles, *a*, *b*, *f*, *d*, and *h*, take the yarn of courses 16, 17, and 18, and knit the stitches thereof.

In the tenth revolution of the needle cylinder, FIG. 7, the needles *a*, *b*, *f*, *d*, and *h*, and the now selected remaining intervening bare needles *c*, *e*, *g*, and *i*, pass the feeding station at latch clearing level and take the yarn to form course 19 thereof, the needles *a*, *b*, *f*, *d*, and *h*, forming regular stitches in their wales while the needles *c*, *e*, *g*, and *i*, merely tuck the yarn as shown at 19a to start new wales. All of the needles are now in action and in the eleventh rotation of the needle cylinder, FIG. 8, all the needles pass the feeding station at latch clearing level and take the yarn to form regular stitches in a full course 19b thereof. A sufficient number of courses similar to course 19b are then formed to permit the courses to be sufficiently constricted to close the opening at the center of the fabric 6 and which will now appear as in FIG. 11A. Once a sufficient number of courses have been knit upon all of the needles to form the circular fabric area 6, tension upon the yarn end 5a is discontinued and rotary knitting upon all of the needles continues, with or without a yarn change, to form the adjoining tubular foot portion F of the hosiery. Thereafter, the remainder of the hose, or of the product being made, may continue to be formed in any desired manner. Any desired type of yarn may be used in the formation of the fabric 6 including elastic yarn, stretch yarn of the Helanca type, or relatively non-stretch yarns. While the needle selection and activation of each series of bare needles has been described to indicate that such bare needles are evenly spaced and are midway between already active needles, it should be

understood that they may be activated singly, or as a series in any desired pattern in any desired course of the fabric 6. It is desirable, however, that, in the formation of the selvage course 10, 11, a first group of single spaced needles take the yarn for course 10 and that a second group of single needles alternating with the needles of the first group be activated so that both groups take the yarn to form course 11. Any desired number of courses may be made upon already active needles before selecting other bare needles to join the active needles.

The product shown in FIG. 10 differs from that of FIG. 9 in that there are two full turns of the yarn 5, indicated at 10 and 10a, in the course 11 to form the selvage course. While two such turns of the yarn 5 are shown, it will be understood that there may be more or less than the two full turns 10 and 10a and that less than complete turns of the yarn 5 may also be made. The formation of a multiple number of turns of the yarn 5 in the selvage course will generally cause the fabric 6 to successfully resist opening up at the center thereof when pressure is exerted thereupon. In the making of the selvage course of FIG. 10, the needles a, b, are at the tuck level at the feed for the two rotations of the needle cylinder to take yarn for the turns 10 and 10a thereof, whereas in the making of the selvage course of FIG. 9, the needles a, b, may either be at the tuck or the latch clearing level for the single rotation of the needle cylinder to take the yarn for the single turn 10.

While the above-described product of FIG. 11A may be used by itself to form the toe pocket of hosiery as shown in FIG. 12, to form the toe pocket of hosiery as shown in FIGS. 13 and 14 requires reciprocating knitting upon a number of needles generally about half, of the circle of needles to form narrowed and widened segments of fabric N after the discontinuance of the tension upon the yarn end 5a and prior to such further rotary knitting as may be required to form the foot portion F. In FIG. 13, the circular fabric 6 will thus be positioned above the toes of the nearer of the hose while the segment N will be positioned thereunder, whereas in FIG. 14 their positions will be reversed. The narrowed and widened segments N are made in the same manner in which narrowed and widened heel and toe pockets have heretofore been made upon circular knitting machines. Each segment N has the customary gore line Na therein and extends between the converging dot dash lines Nb and Nc which define the outline thereof. It is within the scope of the invention to have narrowed segments only in place of the narrowed and widened segments N in the toe pockets. The addition of the segments N, in juxtaposition to the fabric areas 6, increases the size of the toe pockets and permits the fabric areas 6 to be placed above or below the toes of the wearer of the hose, in which latter location it is not visible from above when the hose is being worn. The novel toe pocket may be shaped upon the customary hosiery forms and while it is here shown as having been made prior to the formation of the tubular fabric of the foot portion F to which it is joined, it should be understood that the invention is not so limited as to the order in which the novel toe pocket and the adjoining tubular fabric of the foot portion are to be made.

Coming now to the yarn tensioning attachment shown in FIGS. 15 - 21, its purpose is to exert the required tension upon the end 5a of the yarn 5 during the knitting of the latter in the process described in con-

nnection with FIGS. 1 - 10. The initial position of yarn end 5a, before being acted upon by the attachment, may be seen in FIGS. 15 and 18 wherein 21 indicates a customary dial plate disposed just above the needle cylinder 1 and upon which is supported a customary spring clamp 20 which holds the yarn end 5a between it and the dial 21, the yarn end 5a extending between the finger 7 and the clamp 20 when the yarn 5 is not being used.

10 The tensioning attachment is provided with a downwardly extending hook 24 at the free end of its horizontally extending stem 24a, the other end of which is secured to a horizontally movable slide 25, the latter moving radially toward and away from the needle circle 15 along the line 27, FIG. 18, which extends through the center line 27a of the needle cylinder and which is generally normal to the yarn finger 7. The slide 25 is supported upon and is so movable longitudinally of a horizontally extending rod 26 extending between, and supportedly engaged by opposite sides 31 and 31a of a generally U-shaped bracket which has a bottom side 31b and an adjoining lateral brace 31c extending between, and secured to, the like faces of the sides 31, 31a, and 31b. The U-shaped bracket is itself suitably secured to a portion of the knitting machine frame shown at 32.

20 The slide is kept upright in its movement by means of a fork shaped member 28 secured to the underside of the slide and straddling a second guide rod 29 disposed in spaced parallel relation to the rod 26. The rod 29 also extends between, and is supportingly engaged by said sides 31 and 31a while the fork member 28 has an adjusting screw 28a threadedly engaged therein for engagement with the side 31a to limit the movement of the slide 25 toward the needle circle 1. The slide is movable between its forward position of FIGS. 15 and 18, wherein said hook 24 passes through aperture 23 in latch ring 22 to extend within the needle circle to a position just under the periphery of dial plate 21, and its rearward position of FIGS. 16, 17, and 19, wherein said hook 24 moves past a vertically extending base 37a and being retained in said base by a cover plate 37b suitably secured thereto.

30 The base 37a is supportingly secured to said bracket brace 31c, and the blade 37 is shown in raised open 35 yarn receiving position in FIGS. 16 and 20 and in lowered yarn clamping position in FIG. 17. The clamping blade 37, which has a yarn receiving opening 37c therein as shown in FIG. 20, is raised and lowered by means of a lever 38, FIG. 16, suitably pivotally 40 mounted at the upper end of a bracket 38a which is supportingly secured to said brace 31c, the forward end 38c of said lever 38 extending through suitably formed vertically extending slots in said base 37a and plate 37b and through a suitably formed aperture in the blade 37 whereby raising and lowering of said end 38c will cause said blade 37 to be moved therewith. The end 38c of said lever is movable to its full line position to hold said blade 37 in its raised open position by means of a suitably disposed cable 38d operatively connected to and suitably arranged between the opposite end of lever 38 and the pattern drum D of the machine, a suitable cam on the drum acting to hold the lever 38 in its full line position. The end 38c is movable to, and is held in its lowered phantom line position, when the drum D so permits, by a spring 38b anchored to the lever 38 and to the bottom side 31b of the bracket thereby to hold blade 37 in its lowered yarn clamping position.

The slide 25 is urged toward the needle cylinder 1 by a compression spring 30 encircling the rod 26 between the slide and the side 31 of the bracket, FIGS. 15 and 18. A cable 33 attached to the underside of the slide 25 extends horizontally to, and downwardly over, a pulley 34 which is suitably pivotally supported between the sides of a U-shaped bracket 34a attached to the bracket side 31, the cable also being attached to a counterweight piston 35 vertically movable in an encircling cylinder 36, the latter also being supportedly secured to said side 31. The counterweight is sufficient to compress the spring 30 and to move the slide 25 to its rearward position shown in FIGS. 16 and 17. To permit the spring 30 to move the slide 25 to its forward position of FIGS. 15 and 18, the gravitational effect of the counterweight is nullified by compressed air entering the lower end of the cylinder 36 through a port 36a to raise the piston 35 to the position shown in FIG. 15 against the stop screw 35a which extends interiorly of the cylinder 36.

The compressed air to raise the piston 35 may come from any suitable source, such as the exhaust side of a suction fan F of the type customarily used in circular knitting machines, the air being suitably piped from the fan F to the port 36a and being suitably controlled by a valve VI in the pipe line and which is opened and closed at the proper times by means of suitable operative connections between the valve VI and the pattern drum D of the machine. Obviously, when the valve VI is closed, the piston will descend and move the slide 25 to its rearward position.

Sufficient parts of the yarn clamping and tensioning attachment have been described so that the operation thereof to place the yarn end 5a in the clamp 37 may now be set forth, after which the means to tension the yarn will be set forth and its operation described.

With the parts in their positions as shown in FIGS. 15 and 18, with the hook 24 in forward position, with clamp 37 opened and with all of the now bare needles 2 at welt level, knitting of a hose is started by lowering the finger or guide 7 into feeding position with the yarn end 5a extending therefrom to the clamp 20. Thereafter, two or three adjacent or relatively closely spaced needles 2a of the rotating circle of needles are raised to yarn taking level so that as they pass by the guide 7, these needles 2a will take the yarn 5 and carry it around the machine as the needle circle rotates, these needles meanwhile having been lowered to welt level so that the yarn 5 taken by the needles is held securely between their lowered hooks and the throats of the now advanced sinkers 3. As rotation continues, the yarn end 5a is drawn from under the clamp 20 with the yarn now extending between the guide 7 and the rotating needles 2a. As the needles move under and past the hook 24, the so extending yarn 5 is caught within the hook 24, at which time the slide 25, under the influence of the gravitational effect of the counterweight 35 as caused by closure of the valve VI by the pattern drum D and venting of the compressed air from the cylinder 36 moves rearwardly along the rods 26 and 29 to its position of FIGS. 16 and 19 wherein the hook 24 and the bight of yarn 5 therein have moved past the opened clamp 37, drawing the doubled-over yarn through the aperture 23 in the latch ring 22 in so doing. At the same time the needles 2a have moved further around, as the needles rotate, to their positions in FIGS. 16 and 19 and the doubled yarn in the hook 24 is within the open-

ing 37c of opened blade 37, see FIG. 20. Also, at this time, the drum D is indexed to release its pull on cable 38d and on lever 38 whereby the spring 38b will act to lower the end 38c of the lever 38, thereby also to lower, and to keep lowered, the clamping blade 37 with the bight of yarn 5 therein, the yarn being held between the blade 37 and its base 37a and plate 37b, as shown in FIG. 17, the lever 38 not being shown in this view. Thereafter, in the continued rotation of the needle circle, the needles 2a rise to release the yarn end 5a which, having been under some tension, now snaps back through the aperture 23 to the vicinity of the clamp 37 leaving the yarn end in the clamp and extending therefrom, through aperture 23, to the guide 7. In this manner the yarn end 5a has been transferred from the clamp 20 inside the needle circle, through the aperture 23, to the clamp 37 spaced from the needle circle.

Meanwhile, it is necessary to apply yieldable tension to the yarn 5 between the clamp 37 and the latch ring 22 and for this purpose, there is provided, at a position nearer to the axis 27a of the needle cylinder 1 than is the position of the clamp 37, a yarn engaging pulley-like small roller 39, rotatably journaled upon one end of a shaft 39a secured in, and extending through, the free end of an arm 40, said shaft 39a being at right angles to the plane of said rods 26 and 29 and of said arm 40.

A fixed position second roller 39b, similar to roller 39, is rotatably mounted at the upper end of a vertically extending member 39c secured at its lower end to brace 31c, the two rollers being spacedly aligned with the horizontally extending yarn 5, FIG. 19. The other end of arm 40 is pivotally mounted at 41 on one face of a vertically movable slide 42 which is so movable along a vertical guide rod 43 extending therethrough, the slide 42 having a horizontally extending arm 44 secured thereto and terminating in a forked end which straddles a second vertical guide rod 45 parallel to the rod 43. The upper ends of said guide rods are spacedly secured in a horizontally extending member 47 of which an end thereof is anchored in a suitable support 32a, the lower ends of said rods being anchored in a suitable support 32b, FIG. 17. The arm 40 and roller 39 are urged downwardly by a spring 46, anchored to said arm and to said slide 42, and are limited in such movement, FIG. 16, by the extension of shaft 39a coming into contact with the upper side of arm 44, FIGS. 18 and 19.

A flexible cable 48, connected to the slide 42, extends upwardly over a pulley 48a and then downwardly to be connected to a vertically movable counterweight piston 49, the latter being so movable within an encircling vertically extending and suitably supported cylinder 50, the closed upper end of which is provided with an aperture through which said cable 48 passes and upon which said pulley 48a is mounted. The cylinder is provided with an internally extending stop 50a to limit the upward movement of the piston 49. The counterweight 49 is such that the weight of the slide 42 overcomes the effect thereof, and is movable downwardly, FIG. 21, by gravity, the slide 42 being returned to its upper position of FIG. 20 by compressed air entering a port 51 at the upper end of the cylinder 50 to act upon, and to lower, the piston 49 which, in turn, raises the slide 42. The compressed air may be suitably piped from the outlet side of the suction fan F to the port 51 and its flow may be controlled by a valve V2 in the pipe

line, the valve being opened and closed as required by a suitable operative connection between the valve and the pattern drum D of the machine. Obviously, when the valve V2 is closed, the slide 42 will be free to move downwardly.

The tension is applied to the yarn 5 by deflecting the same downwardly from its horizontal position between clamp 37 and latch ring 22 by means of the roller 39. This starts with slide 42 in its raised position of FIG. 16, at which time the indexing drum D causes the valve V2 to be closed, thus permitting the slide 42 to commence its downward movement and causing the V-shaped periphery of roller 39 to engage, to press against and to deflect the yarn 5 downwardly. At the same time, the yarn is supposedly engaged in the V-shaped periphery of roller 39b over which it moves, FIG. 17. As the slide moves downwardly, the yarn 5, held by and extending between clamp 37 and its point of attachment to the fabric 6, is subjected to the tension required to construct the courses of fabric 6 as they are being knitted in the manner set forth. The arm 40 and the roller 39 initially swing upwardly and then rock upwardly and downwardly under the opposing influences of the net weight of the slide 42 and of the tension in the spring 46, thereby evening out the tension exerted upon the yarn end 5a as the portion thereof attached to the start of fabric 6 moves in a circular orbit with the rotation of the needle cylinder. This assures that the yarn 5a will not be broken as it reciprocates through the aperture 23.

When the process of forming the fabric 6 is virtually complete and the slide 42 nears its lowermost position, as indicated by the phantom line position of the roller 39 in FIG. 17, the yarn end 5a is severed to discontinue the tension thereon so that further knitting may then continue upon the needle cylinder to make tubular fabric. While any desired means may do the severing, in the present instance, this is done with a heatable resistance wire 8 supported by the bracket side 31a in close proximity to the underside of the yarn 5, FIGS. 17 and 16, the wire 8 being in a circuit which includes a source of electrical power 8a and a switch 8b which may be operatively connected to the drum D of the machine whereby the latter, as it is being indexed, will open and close the switch 8b as may be required to heat the wire 8 when it is desired to sever the yarn 5 at the time above indicated. The severed portion of the yarn still attached to the fabric 6 will be pulled through the latch ring 22 to the inside of the needle circle.

Once the yarn 5 has been so severed, it is desirable to remove the waste portion thereof, one end of which is still in the clamp 37 with its other end free in the vicinity of the lowered pulley 39. For this purpose there is provided a suction tube 9 having an upturned end 9a in the vicinity of the lowered pulley 39 and which will, when operative, cause the waste yarn to enter therein, to pass therethrough and then to be discarded, the clamp 37 being opened at the proper time by the action of drum D on lever 38 to release the yarn therein to permit such disposal of the waste yarn end. Suction may be provided in the tube 9 by any suitable means, such as by connecting the tube 9 to the intake side of the suction fan F and controlling the flow in the tube 9 by means of a valve V3 therein, the valve being opened and closed at the required times by suitable operable connections between the valve and the drum D of the machine.

The valve V3 is then closed to discontinue the suction in tube 9, the clamp 37 is retained in opened position, the valve V2 is then opened to raise slide 42 to its uppermost position, the wire 8 is retained in unheated condition and valve V1, after each stocking has been completed and cast off from the needles 2 with the yarn 5 in the clamp 20, is opened to permit the slide 25 to place hook 24 through the latch ring 22, whereby the apparatus is ready for the start of its next cycle of operation.

WHAT I CLAIM IS:

1. Method of knitting upon a circle of needles of a circular knitting machine which comprises holding the starting end of suitable yarn, interlacing the remainder 15 of said yarn into first a selvage course and then knitting a plurality of following circular courses of said yarn by rotary knitting upon previously bare needles of said circle of needles whereby to form a circularly knit fabric, the initial end thereof including an opening as said 20 courses are being knit, and exerting tension upon said starting end of said yarn during the formation of said courses thereby to reduce the diameters thereof and to close said opening in said fabric whereby the latter forms a circularly shaped fabric area extending across and covering the bore of said circle of needles.

2. Method of claim 1 which includes forming a plurality of turns of said yarn in said selvage course.

3. Method of claim 1 wherein said selvage course is formed upon a portion of the needles of said circle of 30 needles and wherein said courses are formed upon progressively increasing numbers of needles the range of which is from said portion of the needles to all of the needles of said circle of needles.

4. Method as in claim 3 wherein a number of courses 35 of said plurality of courses are formed upon each of said progressively increased numbers of needles.

5. Method as in claim 1 which includes discontinuing said tension upon said starting end of said yarn and knitting tubular fabric upon needles of said circle of 40 needles.

6. Method as in claim 5 wherein said circularly shaped fabric area and said tubular fabric constitute a foot portion of hosiery having a closed toe pocket provided by said circularly shaped fabric area and having 45 instep and sole areas provided by said tubular fabric.

7. Method as in claim 1 which includes discontinuing said tension upon said starting end of said yarn and reciprocatingly knitting a plurality of partial courses upon a portion of the needles of said circle of needles 50 to form an additional fabric area in juxtaposed relation to said circularly shaped fabric area, and knitting tubular fabric upon needles of said circle of needles.

8. Method as in claim 7 wherein said juxtaposed fabric areas and said tubular fabric constitute a foot portion of hosiery having a closed toe pocket provided by 55 said juxtaposed fabric areas and having instep and sole areas provided by said tubular fabric, said pocket having under-the-toe and over-the-toe sides of which one of said sides is provided by said additional fabric area and the other of which is provided by said circularly shaped fabric area.

9. In a circular knitting machine of the type including a needle cylinder and a yarn guide, the improvement comprising means to knit a yarn into a flat, single ply, circular disc of fabric covering the bore of said needle cylinder, said means including the combination of a needle activating means for activating only a first group 60

of needles while feeding the starting end of a yarn thereto to form a first course of fabric and thereafter activating said first group and progressively increasing numbers of groups of needles during knitting of successive courses during the formation of said fabric disc whereby the number of wales in the courses of said fabric disc progressively increases, and a yarn tensioning means engaging said starting end of said yarn and withdrawing said yarn outwardly from said needle cylinder during knitting of said disc to diametrically constrict the courses of said fabric disc whereby a central opening in said disc is gradually closed as said disc is formed.

10. A knitting machine as in claim 9 having a first clamp to hold said starting end of said yarn prior to knitting said fabric, said means yarn tensioning having a second clamp and being operative to transfer said starting end of said yarn from said first to said second clamp to be held therein whereby said starting end of said yarn extends between said guide and said first clamp prior to said knitting of said fabric and whereby said starting end of said yarn extends between its point of engagement with said fabric and said second clamp during said knitting of said fabric.

11. A knitting machine as in claim 10 wherein said first clamp is inside said circle of needles and wherein said second clamp is spaced therefrom.

12. A knitting machine as in claim 10 having an additional guide for said starting end of said yarn.

13. A knitting machine as in claim 12 wherein said additional guide is positioned adjacent the periphery of said circle of needles.

14. A knitting machine as in claim 12 having a latch ring and wherein said additional guide constitutes an aperture in said latch ring.

15. A knitting machine as in claim 12 wherein said starting end of said yarn extends directly from said guide to said first clamp prior to said transfer of said starting end of said yarn and wherein said starting end

of said yarn extends from said guide to, and through, said additional guide to said second clamp after said transfer of said starting end of said yarn.

16. A knitting machine as in claim 10 wherein said circle of needles rotate and wherein certain of said needles are operative to take said yarn whereby said yarn extends between said guide and said rotating certain needles prior to said transfer of said starting end of said yarn, said yarn tensioning means having a hook and being operative to cause said hook to engage and to pull said yarn extending between said guide and said certain needles thereby to transfer said starting end of said yarn from said first to said second clamp.

17. A knitting machine as in claim 16 having an additional guide for said so-extending end of said yarn, and wherein said yarn tensioning means is operative to cause said hook to engage and to pull said yarn extending between said guide and said certain needles through said additional guide thereby to transfer said starting end of said yarn from said first to said second clamp.

18. A knitting machine as in claim 10 having means to sever said starting end of said yarn between its point of engagement with said fabric and said second clamp whereby a waste portion of said yarn remains in said clamp.

19. A knitting machine as in claim 18 having means to remove said waste yarn from said second clamp and to discard the same.

20. A circular knitting machine according to claim 9 wherein said yarn tensioning means includes a clamping means for holding the initial portion of said starting end that is not knit into the fabric and a movable member selectively engageable with the yarn end at a point between said clamp and said fabric for applying a yieldable tension thereto during the formation of said circular disc of fabric.
